(57) **CLAIM**

The ornamental design for a handle for lawn and garden tool, as shown and described.

DESCRIPTION

FIG. 1 is a right front perspective view of a handle for lawn and garden tool in accordance with the claimed design; FIG. 2 is a right front perspective view of the design of FIG. 1 isolated from the lawn and garden tool; FIG. 3 is a right side elevation view of the design of FIG. 2; FIG. 4 is a left side elevation view of the design of FIG. 2; FIG. 5 is a top plan view of the design of FIG. 2; FIG. 6 is a bottom plan view of the design of FIG. 2; and, FIG. 7 is a rear elevation view of the design of FIG. 2. The evenly spaced broken lines showing the battery in FIGS. 1-7 and showing of the battery, pole, loop handle and the lawn and garden tool in FIG. 1 illustrates the environment of the claimed design and form no part thereof. The remaining evenly spaced broken lines in the drawings illustrate portions of the handle for lawn and garden tool and form no part of the claimed design. The dot-dash-dot broken lines in the drawings define the bounds of the claim and form no part thereof.
